SAMUEL BERTRAM SHELDON, OF BETHLEHEM, PENNSYLVANIA, ASSIGNOR TO LACKAWANNA STEEL COMPANY, OF NEW YORK, N. Y.

INTERLOCKING SHEET-PILEING.

1,176,323.

Specification of Letters Patent. Patented Mar. 21, 1916.

Application filed March 17, 1909, Serial No. 484,019. Renewed June 28, 1915. Serial No. 36,914.

To all whom it may concern:

Be it known that I, SAMUEL B. SHELDON, a citizen of the United States, residing at Bethlehem, in the county of Northampton and State of Pennsylvania, have invented new and useful Improvements in Interlocking Sheet-Piling, of which the following is a specification.

My invention relates to steel sheet piling and consists in a rolled interlocking section, particularly adapted to be used with channel-beams of standard shape, whereby a strong continuous wall of piling is produced.

15 My invention is fully shown in the drawing herewith.

Figure 1 is a perspective view of a portion of a wall formed of my peculiar sections arranged alternately with the channels, as is intended. Fig. 2 shows a similar wall in plan. Fig. 3 shows a slight modification in the form of my peculiar section to permit angular adjustment of the sections.

25 The feature of my invention is the interlocking section A of peculiar form adapted to be arranged as shown alternately with channels, or channel beams, B, of usual form to make up the complete wall. These peculiar sections are preferably formed by rolling from the steel billet at one operation in a series of passes, and consist, as an integral article of the web 1, provided correspondingly at each edge with the two 35 flanges substantially as shown; one of said flanges is the "hook" 2 and the other, called the "flange" 3, is offset from the plane of the web and extends substantially longitudinally. The hook and the flange thus form 40 on each edge a pocket or groove 5 of a size and proportions to receive the flange 6 of the channel. The groove may be of the size shown in Fig. 2 substantially to fit the channel flange, with of course, sufficient clearance for easy driving, or may be enlarged 45 as shown in Fig. 3 to permit angular adjustment of the sections, and to afford a space for packing material to render the joints water tight. The hook 2 is reinforced 50 or thickened at the point 7, and tapers therefrom to its tip. The flange is also reinforced at about the point 8 and tapers therefrom.

In the form shown in Fig. 3, the hook is 55 outwardly inclined to permit the inward

and upward swing of the channel flange in angular adjustment, for the same reason the flange 3 may be slightly curved downwardly leaving the recess 9 in its upper surface for the corner of the channel.

60 My piling is easy and economical to manufacture, convenient for use as it utilizes standard beams, and produces a strong and compact wall with the webs substantially in alinement.

65 Having thus described my invention, what I claim is,—

1. Interlocking steel sheet piling sections adapted to be arranged alternately with channels to form a continuous wall and 70 comprising each a web and on each edge thereof a hook and a flange, the hook being inclined to the plane of the web and the flange being slightly downcurved from said web to permit a limited amount of angular 75 adjustment to the channels.

2. Interlocking steel sheet-piling sections adapted to be arranged alternately with channel beam sections to form a continuous wall, and comprising each a web and on each 80 edge thereof a hook and a flange, the hook being inclined to the plane of the web and the flange slightly downwardly curved forming an enlarged groove on each edge to receive the channel flange and permit relative angular adjustment of the adjacent sections, said hooks and flanges being thickened adjacent the web and tapering therefrom.

3. Interlocking steel sheet-piling sections, adapted to be arranged alternately with channels, said sections comprising a web and on each edge thereof a hook and a flange, the hooks extending on one side of the web and the flanges on the other, said 90 flanges being thickened adjacent to the web and tapering therefrom to their edges and being offset from the plane of the web so that the webs of the sections and the channels may lie substantially in the same plane. 95

4. A wall of interlocking steel sheet piling, comprising structural steel channels and peculiar sections adapted to be arranged alternately with the sections comprising each a web and both edges thereof correspondingly formed with a continuous hook and continuous flange, said hooks and flanges being thickened adjacent the web and tapering therefrom, the hooks extending 105 one side of the web and the flanges on the 110

other, and the flanges being offset from the web so that, in the completed wall, all the webs may lie substantially in the same plane, the hooks extending substantially at 5 a right angle to the wall and the flanges extending substantially parallel thereto.

5. A wall of interlocking steel sheet piling comprising integral rolled sections of two forms alternately arranged, one form 10 being structural channels of usual shape, the other form having a web and on each edge thereof a hook and a flange the hook extending substantially at a right angle to the web on one side and the flange extending 15 substantially parallel to the web and offset therefrom on the other side, permitting the webs of the alternate sections to lie substantially in the same plane, said flange being thickened at its base.

20 6. A wall of interlocking steel sheet piling comprising integral rolled sections of two forms alternately arranged one form

being substantially of standard shape, the other form having a web and on each edge thereof a hook and a flange, the hook shank 25 extending on one side of the web and having its tip turned outwardly and extending back toward the plane of the web, the outer surface of the hook being formed in substantially a semi-circle, and the flange offset 30 from the web on the other side and extending substantially parallel thereto, permitting the webs of the alternate sections to lie substantially in the same plane, said flange being substantially elongated beyond the 35 plane of said tip to engage with the back of the channel.

In testimony whereof I have signed my name to this specification in the presence of two subscribing witnesses.

SAMUEL BERTRAM SHELDON.
